UNITED STATES PATENT OFFICE

CHARLES H. FRANZ, JR., OF MILWAUKEE, WISCONSIN

LOOSE-LEAF BINDER

Application filed June 5, 1925. Serial No. 35,084.

This invention relates to loose leaf binders.

Objects of this invention are to provide a loose leaf binder in which the cover and back are equipped with members, one of which carries posts adapted to be projected through the sheets and to provide a slide or locking means carried by the other of said members adapted to lock the free ends of the 10 posts in position.

Further objects are to provide a binder in which the parts are non-removable and cannot become lost, and in which the locking of the posts may be most easily effected in a simple and rapid manner with a minimum of effort on the part of the operator.

Further objects are to provide a loose leaf binder in which auxiliary flaps are carried adjacent the rear edge of the covers, one of 20 these flaps being provided with a plurality of posts which are adjustable and equipped with heads, the other of such flaps being provided with marginally opening latches adapted to receive such heads by a sliding motion 25 and to thereafter lock such heads securely in position.

An embodiment of the invention is shown in the accompanying drawings, in which:—

Figure 1 is a fragmentary view partly in 30 section showing the locking slide and a portion of the enclosing sheath.

Figure 2 is a sectional view through the binder.

Figure 3 is a section on the line 3—3 of Figure 2.

Figure 4 is an enlarged detail view partly in section showing the cooperation of the slide and the headed posts.

Referring to the drawings, it will be seen 40 that the binder is provided with a back 1 which is joined to a pair of covers 2. The back is composed of a pair of flexible members which are secured together and which continue over the inner and outer faces of the 45 covers to form an enclosing covering therefor. Preferably these portions are extended to provide flaps 3 and 4 which project outwardly from the back and are positioned between the covers when the binder is closed. 50 The flaps 3 and 4 enclose respectively a sheath

5 and a metal strip 6, as shown most clearly in Figures 2 and 3. This sheath is preferably made by a longitudinally folded metal strip, as illustrated in the drawing.

The strip 6 rigidly carries a plurality of 55 posts 7, such posts being secured to the sheath in any suitable manner. For instance, as shown in Figure 3, the posts may be provided with flanges 8 and with headed portions 9' which grip a portion of the strip. These 60 posts are each provided with a telescopic member 9 which is in turn provided with a head 10 formed by constricting the portion of such post adjacent the head, as shown in Figure 3. Preferably, the members 9 are externally threaded and cooperate with the internally threaded hollow portion of the post 7, as shown in Figure 2, to thus permit adjustment of the length of the post. Preferably one or more auxiliary posts 11 are provided intermediate the posts 7 to relieve such 65 latter posts of some of the strain due to the leaves 12 and also to provide additional points of attachment for the leaves. The sheath 5 is provided with a plurality of slits 70 13 which extend transversely across its bottom sides and open through its marginal edge, as most clearly shown in Figure 1. These slots are adapted to permit the passage therethrough of the heads 10 of the posts. 75 A slide 14 is positioned within the sheath 5 and is provided with a manipulating portion 15 projecting from one end of the sheath 5. This slide is provided with a slot 16 which cooperates with a pin 17 to retain the slide 80 in position within the sheath while permitting a limited motion. The slide 14 is provided with right angle slots, as shown in Figure 1, which are each composed of a transversely extending relatively large portion 18 and with a longitudinally extending constricted portion 19. The portion 18 of the 85 slots is adapted to align with the slots 13 formed in the sheath 5 when the slide is in one extreme position, and to permit the entry of the heads 10 of the posts. Thereafter, the slide 14 is moved longitudinally of the 90 casing 5 and the portions 19 of the slots engage below the heads 10 of the posts and receive the constricted portions of such posts. 100

An auxiliary strap-like member 20, (see Figure 2) is provided which is equipped with thimbles 21 adapted to slide over the post 7 to facilitate positioning and removal of the sheets. When the binder is opened, the requisite number of sheets may be held upon the thimbles 21 and such sheets, and thimbles, and plate 20 may be bodily removed, thus retaining the removed sheets in alignment and facilitating their repositioning.

In using the binder, the sheets are positioned as desired and, thereafter, the back is rocked into the position shown in Figure 3. It is a simple matter to slide the sheath 5 laterally across the heads of the posts 7 with such heads positioned within the slots 13. This is a very simple operation and does not require bodily lifting of the sheath 5 upwardly and then positioning such sheath by a downward motion. Instead, the sheath is slid laterally, as stated, and the headed ends of the posts slid into position. Preferably the sheath 5 is provided with upwardly struck recessed portions 23 to receive the heads of the posts. After the posts are in position, the slide 14 is pushed longitudinally of the sheath into the position shown in Figure 1, thus locking the heads of the posts in position.

It will be seen that an adjustment is provided by the telescopic formation of the headed posts to permit variation of the thickness of the binder within certain limits.

It will be seen that a loose leaf binder has been provided which may be very easily opened and closed, and locked in closed position as the flexibly joined flaps for holding the sheaths 5 and 6 may be most easily manipulated to facilitate this operation.

In addition to this, the provision for lateral sliding of the sheath 5 greatly facilitates the positioning of the headed posts within such sheaths.

Although the invention has been described in considerable detail, it is to be understood that the invention may be variously embodied and is, therefore, to be limited only as claimed.

I claim:

1. A loose-leaf binder comprising a pair of covers, a metal strip secured to one of said covers, headed posts carried by said strip, a sheath carried by the other of said covers and formed by folding a metal strip upon itself, said sheath having transverse slots formed in its inner face and extending through the marginal fold for reception of said post heads, the outer portion of said sheath being imperforate and having pockets formed therein in alignment with the inner ends of said transverse slots, said pockets adapted to receive and encase said post heads, and a slideable locking member housed within said sheath and adapted to engage said post heads to retain them in said sheath.

2. A loose-leaf binder comprising a pair

of covers, a metal strip secured to one of said covers, headed posts carried by said strip, a flattened tubular sheath carried by the other of said covers having transverse slots formed in its inner wall terminating short of one longitudinal edge thereof and extending through the other edge thereof to the outer wall of said sheath, said outer wall being imperforate, the slots receiving the headed ends of said posts, and a slideable locking member housed within said sheath and adapted to engage said post heads to retain them in said sheath.

In testimony that I claim the foregoing I have hereunto set my hand at Milwaukee, in the county of Milwaukee and State of Wisconsin.
